C. R. ELLIOTT

WATER COOLING DEVICE

Filed Feb. 13, 1928

INVENTOR.
Clifford R. Elliott

BY

Frank J. Damm
ATTORNEY

UNITED STATES PATENT OFFICE.

CLIFFORD R. ELLIOTT, OF DETROIT, MICHIGAN.

WATER-COOLING DEVICE.

Application filed February 13, 1928. Serial No. 253,920.

My invention relates to a new and useful improvement in a water cooling device adapted for installation in a dwelling or other similar building in which the water pipes are 5 extended in exposed condition in the basement or other heated compartment. When the water is drawn from the faucet at the service end of the pipes in such an installation the water is at a temperature substantially 10 the temperature of the basement or compartment in which the exposed pipes are extended, and in order to procure cool water it is necessary that considerable water be run off from the service end prior to using. This 15 condition exists at all seasons of the year, and particularly in the wintertime, when the basement is heated by the furnace or other heating plant installed therein.

It is an object of the present invention to 20 provide a container which may be embedded in the cool earth beneath the floor of the basement or compartment, so that a quantity of water will be provided which will be maintained at a low temperature so that when 25 the water is led off at the service end, the cool water is obtained quite quickly, the delivery pipe passing directly from the cooler to the service end and faucet.

It is another object of the invention to 30 provide a container of this class having a coil projecting downwardly therefrom.

Another object of the invention is the provision of a container provided with radiating points or fins at its periphery.

Another object of the invention is the provision of simple and effective means of supporting the container in the opening formed in the earth so as to protect the coil projecting downwardly therefrom from injury 40 resulting from the weight of the upwardly positioned tank pressing thereon.

Other objects will appear hereinafter.

The invention consists in the combination and arrangement of parts hereinafter described and claimed.

The invention will be best understood by a reference to the accompanying drawings which form a part of this specification and in which,

Fig. 1 is a central vertical sectional view of the invention.

Fig. 2 is a sectional view taken on line 2—2 of Fig. 1.

In the drawings I have illustrated the invention mounted in an opening 7 formed in 55 the earth 8 and the concrete floor 9. Positioned in this opening is a container 10 which is provided on its periphery with outwardly projecting pointed ribs 11, as shown in Fig. 2, these ribs or pointed periphery facilitating 60 radiation, and consequently increasing the efficiency of the container 10 as a cooler. A cap 12 is secured to the lower end of the container 10 and provided with a threaded neck 13, projecting outwardly therefrom, which 65 is provided with a passage communicating with the interior thereof. Connected in communication with the passage in the neck 13 by the coupling 14 is a coil 15 which is connected to the pipe 16 which is, in turn, connected to the delivery pipe 17 which extends to the faucet or service end thereof. Mounted on the upper end of the container 10 is a cap 18, leading into which is the pipe 19 connected with the source of water supply. In 70 order to support the tank 10 in elevated position so that it will not rest upon the coil 15, I have provided a pair of cooperating members 20 and 21, the ends of which are angularly turned and adapted to lie in engagement with each other and secured together by means of the bolts 22.

These outwardly projecting ends form supporting arms which engage the concrete floor 9 and the upper surface of the embracing 85 portion of the members 20 and 21 will engage the lower edge of the cap 18, thus affording a support for the container 10.

A device constructed and installed in the manner indicated is one which proves quite 90 efficient for the purposes intended, and affords a quick delivery of cold water at the service end of the pipe, while at the same time, economizing on the consumption of water, in that, in order to procure cold water, 95 it is not necessary to run off such a quantity.

It is believed evident that the supporting means is one which may be easily and quickly installed, thus permitting an economical installation of the device.

While I have illustrated and described the preferred form of my invention, I do not wish to limit myself to the precise details of structure shown, but desire to avail myself of such variations and modifications as come 105 within the scope of the appended claim.

Having thus described my invention, what I claim as new and desire to secure by Letters Patent is:

A device of the class described, comprising: a container; a coil depending from and in communication with said container; a pair of cooperating supports embracing said container; angularly turned ends on each of said

supports projecting outwardly beyond the periphery thereof; and a cap secured to the upper end of said container and engaging at its lower edge the upper edge of said supports.

In testimony whereof I have signed the foregoing specification.

CLIFFORD R. ELLIOTT.
